(57) **CLAIM**

The ornamental design for a biometric sensor, as shown and described.

DESCRIPTION

FIG. 1 is a front view of the biometric sensor showing the new design;

FIG. 2 is a back view of the biometric sensor;

FIG. 3 is a top view of the biometric sensor;

FIG. 4 is a bottom view of the biometric sensor;

FIG. 5 is a side view of the biometric sensor;

FIG. 6 is a perspective view of the biometric sensor from the bottom to the top; and,

FIG. 7 is another perspective view of the biometric sensor from the top to the bottom.

Phantom lining, where utilized, is for illustrative purposes only and is not intended to limit the claimed design to the features shown in phantom.
